UNITED STATES PATENT OFFICE.

JOSEPH GALAMB AND EARL P. OSWALD, OF DETROIT, MICHIGAN, ASSIGNORS TO FORD MOTOR COMPANY, OF DETROIT, MICHIGAN, A CORPORATION OF MICHIGAN.

DIMMER.

1,400,811.

Specification of Letters Patent. Patented Dec. 20, 1921.

Application filed May 20, 1918. Serial No. 235,701.

To all whom it may concern:

Be it known that we, JOSEPH GALAMB and EARL P. OSWALD, both citizens of the United States of America, and residing at Detroit, in the county of Wayne and State of Michigan, have invented certain new and useful Improvements in Dimmers, of which the following is a specification, reference being had therein to the accompanying drawings.

10 In the use of automobile lights wherein dimmers are employed to reduce the glare when passing through cities or in heavy traffic, it is desirable that means be employed which do not overload the generator and that 15 effects its purpose even when one of the lights of the circuit or more than one, are accidentally cut out through being burnt out or the like.

This invention relates to a dimmer for automobiles having an A. C. generator, whereby an impedance is afforded which cuts down the effective current passing through the lamp, without overloading or increasing the load of the generator and which also takes 25 care of any lamps on the circuit if others are accidentally burnt out or destroyed.

The invention consists in the matters hereinafter set forth, and more particularly pointed out in the appended claims.

30 In the drawings,

Figure 1 is a plan view partially broken away and in section, of a device embodying features of the invention;

Fig. 2 is a view, partially in elevation and partially in section, taken at right angle to the view in Fig. 1;

Fig. 3 is a view in detail of laminations forming a coil core;

Fig. 4 is a plan view of the laminations; Fig. 5 is a view in detail of a clip for retaining the laminations, and applied coils;

Fig. 6 is a clamp co-operating with the clip to maintain the laminations and coils in proper relation;

Fig. 7 is a diagrammatic view showing the connections when the automobile lights are bright;

Fig. 8 is a diagrammatic view showing the lack of effect of the burning out of one of the lights; and

Fig. 9 is a diagrammatic view showing the light circuits with the dimmer in operation.

Referring to the drawings, a coil core is built up of sheets or laminations of magnetic material, each lamination consisting of

a section 1 and a section 2 which when in contact on the medial line 3 thereof provide core apertures 4, therethrough because of registering notches or gains on the line of division, there being lugs 5 and 6 on the 60 ends of the sections for holding the outer portions of the coils. While the line of cleavage of the two sections, as indicated at 3, is medial, it is off center and the stack as indicated in Fig. 3, is formed by assembling 65 the units in reverse alternate overlapping relations, around a central choke coil or winding 7, an outer circuit coil or winding 8 at one end and a companion circuit coil or winding 9 at the other. When so assembled, the stack is slipped into a holder or clip 10 which is in the form of a channel bar or the like bent to have a pair of end arms 11 and 12 at right angles to the middle portion, so that the assembled coils and laminations 75 may be readily dropped into place therein, the lugs 5 and 6 which retain the coils carrying the windings 8 and 9, also holding the laminations and coils centrally in the member 10. A member 13 is secured upon the 80 member 10 by bolts or the like passing through slots 14 at the ends thereof, and corresponding slots 15 in outturned lugs 16 of the member 10, the whole being incased if desired.

85 The circuit coil or winding 8 is reversely wound to the circuit coil or winding 9 so that the magnetic flux through the laminations produced by winding activity is in the same direction through the central leg of the core. 90 These circuit windings are connected in parallel through a switch 17 with an alternating current generator 18 which is grounded and are severally in series with the headlights 19 and 20 as indicated. A few turns 95 21 and 22 of a separate winding carried by the outer legs of the core—which legs also carry windings 8 and 9—are in series with a tail light 23. As the candle power requirements of the tail light are materially less 100 than those of the headlights, the tail light line, including windings 21 and 22, is of high resistance value—indicated by the light lines in Figs. 7 to 9, inclusive.

As a result, when the switch is turned as 105 indicated in Fig. 7, the headlights 19 and 20 and the tail lights 23 are energized by a current which is impeded only to a slight extent through the windings 8 and 9 by the magnetic flow set up through the lamination-

tions of the core. If one of the lights, as for example 20 (indicated in Fig. 8) burns out or is thrown out of circuit, tending to increase the amount of current on the active 5 lamps due to the drooping volt-ampere characteristic of the generator, the other light 19 is not seriously affected as increase of current through the companion winding 9, causes an increase in the magnetic flux of 10 the field with consequent increased impedance and lessened flow to the lamp.

The central choke coil 7 is connected in series parallel with the lamps 19 and 20 as indicated in Fig. 9 when the switch 16 is 15 drawn to the position shown in Fig. 9 on the terminal or switch point 24. As a consequence the current flow through the choke coil 7 induces a magnetic flow through the central leg of the laminations, augmenting 20 that produced by the windings 8 and 9, thereby increasing the counter E. M. F. effect on such windings. Because of this and in consequence of the counter E. M. F. induced in coil 7, both lights are dimmed 25 as indicated in Fig. 9 and the tail-light also is slightly affected although magnetic inductance of the few turns in series with this light is so slight as to have little effect on this circuit branch. If either light 30 breaks down or is thrown out, when the impedance coil is in operation, the increase of current in the other lamp winding compensates by intensifying the magnetic flux produced by the windings, thus maintaining the 35 impedance effect and thereby protecting the remaining lamp from over-current.

In case both headlights are burned out or accidentally disconnected, the windings of the tail lamp circuit operate to prevent 40 any excess flow through that circuit by producing sufficient magnetic flux as to set up the necessary impedance.

As a result a dimmer is obtained which is effective when the lights are all in operation or cut out, without seriously changing 45 the load in the generator.

The device is light, very compact and easily assembled and placed in the car circuit.

Obviously, changes in the details of construction may be made without departing from the spirit of our invention and we do not care to limit ourselves to any particular form or arrangement of parts excepting 55 such as may be required by the claims.

What we claim is:—

1. In an automobile, the combination of an alternating current generator, lamps supplied thereby, coils each in series with a 60 lamp, a magnetic field energized in common by the coils to retard flow through the latter, an impedance coil adapted to increase the magnetic flow through the fields of the lamp coils and means for throwing the im-

pedance coil into series parallel with the 65 other coils.

2. As a means for varying the candle power of lighting systems for motor vehicles, and wherein the headlight candle power varies from that of the tail light, means for establishing a circuit with the two headlights in parallel with each other and with the tail light, and an impedance coil having a core carrying windings in series with the several lights, said core also carrying a 75 winding adapted to be selectively introduced into said circuit in electrical advance of the individual lamp windings.

3. As a means for varying the candle power of lighting systems for motor vehicles and wherein the headlight candle power varies from that of the tail light, means for establishing a circuit with the two headlights in parallel with each other and with the tail light, and an impedance coil having 80 a core including three legs, two of said legs carrying a winding in a headlight and the tail light branch circuits, with the several headlight windings in parallel, said third leg carrying a winding adapted to be selectively introduced into said circuit in electrical advance of the individual lamp windings, said additional winding being adapted 85 to augment the intensity of the field and vary the candle power of active lamps. 95

4. As a means for varying the candle power of lighting systems for motor vehicles, and wherein the headlight candle power varies from that of the tail light, means for establishing a circuit with the two headlights in parallel with each other and with the tail light, and an impedance coil having 100 a core including three legs, two of said legs each carrying a winding in the headlight and the tail light circuit with the several headlight windings in parallel and wound to produce a flux path extending through the third leg, said latter leg carrying a winding adapted to be selectively introduced into said circuit in electrical advance of the individual lamp windings, said additional winding being wound to augment the intensity of the field produced by the headlight windings. 105

5. In a lighting system for automobiles and in combination, a source of alternating current supply, lamps in series therewith, windings for and within each lamp circuit, a magnetic field formation positioned relative to the windings to produce field activity by 110 current flow within the circuits, the windings being wound to produce counter E. M. F. effects during current activity, and an impedance coil carried by said formation and adapted to be made active at will, said impedance coil, when active, being operative on the field to augment the counter 115 E. M. F. effect on the windings. 120

125

6. A system as in claim 5 characterized in that the field formation includes three substantially parallel core portions with the lamp windings restricted in position to the 5 two outer portions of the formation.

7. A system as in claim 5 characterized in that the field formation includes three substantially parallel core portions with the impedance coil carried by the intermediate 10 portion.

8. A system as in claim 5 characterized in that the field formation includes substantially parallel core portions, with one of the lamp circuits having windings on two 15 of such portions, said latter portions also carrying the windings of two other lamp circuits with the winding of a circuit positioned on a single portion.

9. A system as in claim 5 characterized in that the field formation includes substantially parallel core portions, with one of the 20 lamp circuits having windings on two of such portions, said latter portions also carrying the windings of two other lamp circuits with the winding of a circuit positioned on a single core portion, said single 25 lamp circuit windings being in series.

In testimony whereof we affix our signatures in presence of two witnesses.
